CLAIM

The ornamental design for an electronic tempering faucet, as shown and described.

DESCRIPTION

FIG. 1 is a perspective view of the electronic tempering faucet according to the present disclosure.

FIG. 2 is a front view of the electronic tempering faucet according to the present disclosure.

FIG. 3 is a back view of the electronic tempering faucet according to the present disclosure.

FIG. 4 is a left side view of the electronic tempering faucet according to the present disclosure.

FIG. 5 is a right view of the electronic tempering faucet according to the present disclosure.

FIG. 6 is a top view of the electronic tempering faucet according to the present disclosure; and,

FIG. 7 is a bottom view of the electronic tempering faucet according to the present disclosure.

The broken lines are shown for the purposes of illustrating portions of the electronic tempering faucet and form no part of the claimed design.
